UNITED STATES PATENT OFFICE.

FREDERICK FREMONT ELLIS, OF LOS ANGELES, CALIFORNIA.

DESIGN FOR A TRAFFIC-SIGNAL.

59,726.

Specification for Design.

Patented Nov. 22, 1921.

Application filed May 16, 1921. Serial No. 470,019. Term of patent 14 years.

To all whom it may concern:

Be it known that I, FREDERICK FREMONT ELLIS, a citizen of the United States, and a resident of Los Angeles, in the county of Los Angeles and State of California, have invented a new and original Design for a Traffic-Signal, of which the following is a specification, reference being had to the accompanying drawing, forming part thereof.

The drawing is a front elevation of an automobile signal device showing my new design.

The essential feature of my design consists in providing in a traffic signal device of

the character indicated in the drawing, a license plate holder, a tail-light housing above the holder and having a lens glass opening, and the upper portion of the figure of an officer extending above the housing.

I claim:

The ornamental design for a traffic signal, as described and shown.

Signed at Los Angeles, California, this 7th day of May, 1921.

FREDERICK FREMONT ELLIS.

Witnesses:

CLARENCE B. FOSTER,
H. C. AINSWORTH.
